UNITED STATES PATENT OFFICE.

GEORGE A. MAYER, OF LAKWOOD, OHIO, ASSIGNOR TO THE MANI-FOLD COMPANY, OF CLEVELAND, OHIO, A CORPORATION OF OHIO.

NUMBERING HEAD.

Application filed August 21, 1922. Serial No. 583,093.

To all whom it may concern:

Be it known that I, GEORGE A. MAYER, a citizen of the United States, residing at Lakewood, in the county of Cuyahoga and State of Ohio, have invented a certain new and useful Improvement in Numbering Heads, of which the following is a full, clear, and exact description, reference being had to the accompanying drawings.

10 This invention relates to an improvement in mechanisms known as numbering heads which are used on printing presses for printing serial numbers upon a series of forms or sheets which are being successively advanced through the press either in the form of a continuous web or as individual sheets.

15 The style of numbering head wherein I have shown my invention embodied is designed for use especially upon printing presses of the rotary type.

20 The one serious defect in printing heads as heretofore constructed is their occasional failure to advance the numbering wheels, causing them to repeat a number and thus 25 throw out of order an entire series of blanks, or forms. Sometimes this is not detected until after the job is completed, which renders the entire product of the operation practically worthless. At best, this defect 30 in numbering heads causes a great deal of annoyance, inconvenience, and loss of time, labor, and material.

35 This unreliability of the numbering heads is due to lost motion, or a looseness of parts, in the driving connections between the element which is responsible for the operation of the numbering head, and the pawl carrying member which advances the numbering wheels. It is quite infrequent that trouble 40 occurs in new mechanisms; but after a comparatively short period of service, the parts become worn and the difficulty above pointed out begins.

45 It is the purpose of my invention to provide means that will insure a full and complete stroke of the pawl carrying member regardless of any lost motion which may occur in the driving connections due to the looseness of parts occasioned by wear or other cause. By the provision of such a means, the numbering head is rendered absolutely reliable, and all trouble heretofore caused

by the occasional failure of the numbering head is eliminated.

50 A practical embodiment of the invention is illustrated in the accompanying drawing wherein Fig. 1 shows, in side elevation, a numbering head incorporating my invention and as mounted upon a carrying element or "drum" of a rotary press; Fig. 2 is an end elevation of the numbering head, as though viewed from the plane of line 2-2 and looking in the direction of the arrows, the adjacent end plate of the head being removed; Fig. 3 is a section on the line 3-3 55 of Fig. 2; Fig. 4 is a transverse section through the head on the line a-a of Fig. 1, looking in the direction of the arrows designated 4; Fig. 5 is a section on the line a-a 60 of Fig. 1, looking in the direction of the arrows designated 5; Fig. 6 is a view, similar to Fig. 5, showing the advanced position of the pawl carrying yoke or member; Fig. 7 is an enlargement of a part of Fig. 2; and Fig. 8 is a perspective view of one of the 65 pin carrying arms through which power is transmitted from the rock shaft to the pawl carrying yoke or member.

70 In Fig. 1, the carrying element or so-called "drum" of a rotary press is designated A, and a stationary part of the press, which constitutes the prime actuator of the numbering head or heads, is designated B. This part B may be in the nature of a stationary disk or plate having a cam groove b within 75 which the pin or roller c of an arm C travels. The arm C is secured to the end of a rock shaft D, which extends through the numbering head or heads which is or are secured to the carrying element or "drum" 80 A of the press in transverse alignment. These press parts form no part of my invention, are well known by those acquainted with the printing art, and constitute only 85 one of many apparatuses in connection with which numbering heads of the type shown are adapted for use. Accordingly, further illustration and description of the press is deemed unnecessary except to relate that as the carrying element or "drum" rotates and carries with it the shaft D, the pin or roller c of the arm C travels the groove b of the part B, and said groove is of such a shape 90 as to rock the shaft at predetermined points 95 100

through an angle of movement substantially equal to that required by the pawl carrying yoke or member of a numbering head in order to cause it to properly advance the 5 wheels.

The numbering head, which is of standard type, comprises a housing 1, shown as formed of an integral piece of material and as having end walls 2 and 3 which rise from 10 a base 4 that is shown as having its under surface curved transversely to fit the contour of the carrying element or "drum" A. The base is provided with a dovetail slot 5 which embraces a rail 6 of corresponding 15 shape that is carried by the element or "drum" A. The head is secured to said rail in a properly adjusted position therealong by set screws 7. A sleeve 10 has its ends secured within openings of the end walls 2 20 and 3, as by means of pins or screws 11; and the ends of said sleeve are shown as flush with the bottoms of recesses 12 which are formed in the outer surfaces of the end walls 2 and 3, and which recesses are adapted 25 to be closed by end plates 13 and 14 that are applied to the respective walls 2 and 3. Occupying each of the recesses 12 is a pin 30 carrying arm 16, one of which is shown in perspective in Fig. 8. The hub portion of each of the arms 16 surrounds the shaft 35 D which extends through the sleeve 10 and through aligning apertures in the plates 13 and 14. Each of the arms 16 has a key 17 which occupies the spline or keyway 18 in the shaft D. Pins 20, which extend laterally 40 from the free ends of the arms 16, pass through arcuate slots 21 in the end walls 2 and 3 and have their inner ends engaged within holes in the end branches 22 of the 45 pawl carrying yoke or member 23. The end branches of said member or yoke have bearing apertures that are occupied by the sleeve 10.

From the construction thus far described, 45 it will be seen that upon each oscillation of the shaft D, a like movement will be imparted to the pawl carrying member or yoke 23 by reason of the latter's connection with the shaft through the arms 16 and pins 20.

50 Journalized upon the sleeve 10, between the end branches 22 of the pawl carrying member or yoke, are a plurality of numbering wheels 25, having type 26 embossed on their peripheries. As is usual in such mechanisms, each numbering wheel represents an ordinal of a number, and the type thereof progressing from 0 to 9 thereabout, represent the digits of the ordinal to which the wheel corresponds. Each wheel incorporates a ratchet 28, the same having a tooth 55 for each of the digits, and at some point in its circumference, each ratchet has a relatively deep notch 29 that occurs between two adjacent teeth.

65 A multiple pawl 30 is pivotally connected

at 31 to the pawl carrying member or yoke and it has a tooth 32 which corresponds with and is in the plane of each of the ratchets 28. It will be noted from Fig. 1, that the teeth 32 become gradually shorter from left 70 to right, as the pawl is viewed in Fig. 1, and the same is apparent from Fig. 4. Overthrow of the numbering wheels is prevented by detents 35, pivoted at 36 to the housing 1, the noses of the detents being projected 75 into contact with the ratchets 28 by springs 37 which are contained within recesses 38 of the base 4 and bear against the lower ends of said detents.

As the parts are illustrated, only the longest tooth 32 of the pawl 30 is engaging a ratchet of a numbering wheel. Consequently, when the shaft D is oscillated and the pawl carrying yoke or member accordingly rocked, the numbering wheel whose ratchet 80 is engaged by the longest tooth 32 will be the only one that is advanced, this being the numbering wheel at the left of the series, as the head is viewed in Fig. 1. This wheel will be moved a step each time the shaft D 85 is oscillated, and finally when the longest tooth registers with the notch 29 in its respective ratchet 28, said tooth will enter said notch, allowing the pawl 30 to be rocked by its spring 40 further than before so as to 90 engage the next shorter tooth 32 with its respective ratchet which is that of the second wheel from the left of the series. Consequently, upon the very next oscillation of the shaft D, both wheels under discussion 95 will be advanced one step, after which the longest tooth of the pawl will continue to operate upon its ratchet to the exclusion of the others, the other teeth being held away from their ratchets by the engagement of 100 the longest tooth with the periphery of its respective ratchet. Finally, when the notches 29 of the two left hand end wheels 105 are in alignment, the corresponding teeth of the pawl will be allowed to enter said notches sufficiently to permit the third tooth to engage its ratchet and advance its wheel one step, and so on.

Now it invariably happens after these 110 numbering heads have been in service for a time that certain parts in the driving connections between the prime actuator B and the pawl carrying member or yoke 23 become worn, resulting in sufficient lost motion to prevent the pawl 30 from being oscillated 115 through an angle as great as the angular spacing of the teeth of the ratchets 28, thus giving rise to the difficulty hereinbefore related of the failure of the numbering head to register each time it is actuated.

To overcome such failure, notwithstanding the wear of parts involved in the driving connections, I provide, according to the present embodiment of my invention, a spring 40, which may be constructed of suit- 120 125 130

able resilient wire, coiled at 41 about a peg 42 and secured, as by a screw 43, to the adjacent end wall 3 of the housing. The free end of the spring is arranged to engage one or the other of bearing surfaces designated 45 and 46 that are disposed at an angle to each other. These bearing surfaces in the present instance, are formed by the bottom of a groove 47 which is occupied by the free end of the spring 40. The groove 47 is for the obvious purpose of maintaining the spring in proper relation to the pawl carrying member or yoke at all times. In other words, it forms a guide for the spring. The spring 40, when acting upon the bearing surface 45, insures a full and complete movement of the yoke or member 23 in a direction to retract the pawl. Preferably the shaft D is so adjusted and related to the pawl carrying yoke or member as to insure a full and complete throw of the pawl carrying member or yoke in the wheel-advancing direction. Consequently, all that is necessary to insure proper operation of the numbering head is to impart sufficient initial movement to the pawl carrying yoke or member 23 by the prime actuator to throw said member or yoke over center, so to speak, in the direction to retract the pawl, or until the high point between the bearing surfaces 45 and 46 is moved in the proper direction beyond the free end of the spring 40. The spring will then move it to the full extent of its throw independently of the prime actuator. So long as none of the parts of the driving connections completely gives way, sufficient movement is transmitted therethrough from the prime mover to the pawl carrying member, to insure this initial movement of the pawl carrying yoke or member.

Having thus described my invention, what I claim is:

1. In a numbering head of the character set forth, in combination with the pawl carrying member, means cooperating with said

member to move it to the extreme limit of its movement in a direction to retract the pawl independently of the prime actuator of said member.

50

2. In a numbering head of the character set forth, in combination with the pawl carrying member, a prime actuator for positively moving said member in a direction to advance the numbering wheels and for initiating the return movement of said member, and a spring for completing the return movement of said member independently of the prime actuator.

55

3. In a numbering head of the character set forth, in combination with the pawl carrying member, said member having a bearing surface, resilient means engaging said bearing surface thereby to move said member to the extreme limit of its movement in the same direction but independently of the prime actuator of said member.

60

4. In a numbering head of the character set forth, comprising a housing and a pawl carrying yoke pivotally supported in said housing, one of the end branches of the yoke having a groove and a spring carried by the housing and having its end engaged within said groove, the spring serving to move the yoke to the extreme limit of its movement in a given direction independently of the prime actuator of the yoke.

70

5. In a numbering head of the character set forth, comprising a housing and a pawl carrying yoke pivotally supported in said housing, one of the end branches of the yoke having a guide, and a spring carried by the housing and having its end maintained by said guide in operative relation to said branch of the yoke, the spring acting to move the yoke to the extreme limit of its movement in a given direction independently of the prime actuator of the yoke.

75

In testimony whereof, I hereunto affix my signature.

GEORGE A. MAYER.
